UNITED STATES PATENT OFFICE.

EDWIN E. BARNEY, OF NEW ROCHELLE, AND JOHN H. BARR, OF NEW YORK, N. Y.,
ASSIGNORS TO REMINGTON TYPEWRITER COMPANY, OF ILION, NEW YORK, A COR-
PORATION OF NEW YORK.

TYPEWRITING MACHINE.

Application filed August 18, 1922. Serial No. 582,287.

To all whom it may concern:

Be it known that we, EDWIN E. BARNEY and JOHN H. BARR, citizens of the United States, and residents, respectively, of New Rochelle, in the county of Westchester and State of New York, and the borough of Manhattan, city, county, and State of New York, have invented certain new and useful Improvements in Typewriting Machines, of which the following is a specification.

Our present invention relates to paper feeding mechanism for typewriting machines and its principal object is to provide new and improved mechanism of the character stated.

To the above and other ends which will hereinafter appear our invention consists in the features of construction, combinations of devices and arrangements of parts herein-
20 after described and particularly pointed out in the claims.

In the accompanying drawing:

Figure 1 is a fragmentary transverse sectional view of a typewriter platen carriage
25 embodying our invention.

Figure 2 is a fragmentary view corresponding to Fig. 1 but omitting some of the parts shown therein in order that a better view may be had of other parts.

30 Figure 3 is a fragmentary plan view of the carriage with the platen removed in order more clearly to show parts of our invention.

Figure 4 is a fragmentary transverse sectional view taken on a plane indicated by the dotted lines 1-1 in Fig. 3 and showing the paper feeding devices in released position.

40 Figure 5 is a fragmentary plan view partly in section showing details of construction.

Figure 6 is a fragmentary perspective view of a paper finger and its mountings.

As appears from Figs. 1-3 the carriage
45 of the machine comprises an inclined rear plate composed of top and bottom grooved bars 1 and 2 and connecting webs providing an inclined bar 3. Fixed to the ends of the plate 1-3 are forwardly extending side plates 4, the carriage thus constituted carrying a rotary cylindrical platen 5. The carriage is adapted to travel back and forth along the fixed grooved guide rails 6 and
50 7, roller bearings 8 being interposed between said rails and the grooved bars 1, 2 of the carriage. The preferred manner of mounting the platen on the carriage is disclosed in the application of John H. Barr, Sr. No. 442,790, filed Feb. 5, 1921, each axle section 9 of the platen carrying a sleeve 10 which
55 co-operates with a three-point bearing comprising bearing members 11, 12 and 13 projecting from a seat or depression indicated at 14 in the side plate 4 (Fig. 2). The member 13 of each three point bearing is spring
60 mounted and yieldable so that the axle sections may be withdrawn from their bearings, enabling the platen and axle together to be readily removed without the necessity of loosening any screws or other preliminary
65 operations.

Co-operative with the platen for paper feeding purposes are various sets of pressure and feeding devices, and our invention primarily relates to the means for mounting
70 and controlling said devices. Comprised therein is a main pressure or feed roller device composed of feed roller sections 15 preferably composed of rubber or the like and provided with metal hub portions 16
75 which project beyond the ends of the roller sections. The feed roller sections, of which there are four in the present instance, are frictionally mounted on a rod or shaft 17, and are suitably spaced apart along said
80 shaft. The latter is of small diameter and is flexible to compensate for inequalities occurring in feeding material through the machine. Of course the number of sections may be varied as found desirable. The main
85 feed roller device or sectional feed roller comprising sections 15 co-operates with the underside of the platen at its rear, the shaft or axle 17 of the device being detachably mounted on arms 18, which at their forward
90 ends, as best appears from Fig. 5, are fixedly secured to elongated hubs 19 having flanges
95 20, said hubs being rotatable on a cross rod or bar 21, which extends longitudinally of and below the platen at its forward side,
100 said rod at its ends being received in holes in the side plates 4. The rod 21 is additionally supported on angular brackets each comprising a vertical forwardly extending arm or branch 22, a horizontal forwardly
105 extending arm or branch 23, an upright ver-

tical lip portion 24, and at the top thereof an angularly disposed inclined arm or bar-like portion 25. Each bracket member 22-25 is secured to the rear bar 3 of the platen carriage by headed screws 26. The rod 21 passes through perforations formed in the bracket arms 22 near their forward ends. Cut in the top of each arm 18 at its rear end is a slot or open mouthed seat, indicated at 27, which receives and provides a bearing for the shaft 17, said shaft rotatably engaging in the slots 27. As will be understood from Fig. 3, there are four arms 18 arranged in pairs, and the construction provides that the feed roller device, comprising the sections 15 and the flexible shaft 17, may be detached simply by lifting it out of its open mouthed seats 27. The hub portions 16 of the feed rollers may co-operate with the side portions of the arms 18 to prevent endwise displacement of the feed roller device from its bearings. Also the arms 18 are suitably held against undue endwise displacement, preferably by their hubs 19 in co-operation with each other and other contiguous parts. The flange portions 20 of the two inner hubs may contact for this purpose as shown in Fig. 5. The arms 18 are independently spring pressed in order to maintain the main feed roller device in effective co-operation with the platen, and to this end each arm is provided with a headed pin 28 arranged just forward of the slot 27, said pins projecting laterally outward from their associate arms. The pins 28 provide abutments for bow or U-shaped leaf springs 29 which loosely embrace the hubs 19 at the sides of the associate arms 18, the two branches of each spring extending rearward one above the other, the upper branch terminating in a curved portion which engages with the under side of the associate pin or abutment 28 and is held against lateral displacement by the head thereof in conjunction with the neighboring arm 18. The lower branch of each spring 29 is bent or curved somewhat as shown in Fig. 1 and its free end is supported on the top face of the carriage bar 2, the construction being such that the tension of each spring 29 re-acting against the pin 28 through the upper spring arm, tends constantly to press the arm 18 upward. The springs 29 are self-maintained, that is, they are held in place by friction generated by themselves, and consequently may be readily slipped out of place or removed. The set of independently spring pressed arms 18 serve to maintain the feed roller device 15, 17 in effective engagement with the platen.

The secondary pressure or feed roller device co-operates with the platen 5 forward of the main feed roller device, said secondary device comprising feed roller parts or sections 30, there being four of such

sections 30 in the present instance, all frictionally mounted on a rod or shaft 31, which is flexible to assist in taking care of inequalities occurring during feeding. The feed roller device 30, 31 is rotatably supported on arms 32 of which there are four in the present instance, these arms extending forward and upward from a rock shaft 33 on which they are supported through intermediate devices or hubs 34. These hubs 34, as best shown in Fig. 5, are elongated and each terminates at one end in a flange or circular rib 35. The arms 32 are fixed to hubs 34 and are arranged in proximity each to one of the arms 18. The arms 18 pass over the hubs 34 at one side of the associate arms 32 and said hubs are cut away as indicated at 36, at points where they underlie the arms 18, so that swinging downward movements of said arms 18 will not be interfered with or obstructed by the hubs. The hubs 34 bear loosely on the shaft 33 so that the arms 32 of the secondary feed roller device are pivotally or rotatably supported on said shaft independently of each other. The shaft 33 extends through and bears in the bracket arms 22 and the left-hand end portion of said shaft terminates inside the left-hand end plate 4. The crank arms 32 are formed near their forward or free ends with open mouthed seats or slots, indicated at 37, in which the flexible rod or shaft 31 is seated and rotatably bears. The feed roller device 30, 31 is held in operative contact with the platen by U-shaped springs 38, one associated with each arm 32. Said springs loosely embrace the associate hubs 34 and extend forward parallel with their associate crank arms, the parts or branches of each spring being substantially parallel and arranged one above the other, the lower branch terminating in a curve or hook which rests on and engages with the cross rod 21. The upper branch of each spring engages with a headed pin 39 projecting laterally from the associate arm 32, the inherent tendency of the branches or spring arms being to spread. The result is that said springs are self-maintained or held in place and constantly exert pressure through the pins 39 on the arms 32 and tend to maintain the feed roller device 30, 31 in spring pressed engagement with the platen. The individual mounting of the supporting arms of the two pressure or feed roller devices, as well as the flexibility or yielding of the roller shafts themselves conduce to even feeding of the material or work sheets. For releasing purposes, as hereinafter explained, a connection is provided between the arms 18 and the arms 32, the arms 18 being provided with pins 40 which project laterally outward from said arms near their pivots and engage in slots indicated at 41 formed

in the associate arms 32. The construction is such that motion communicated to the arms 18 will be transmitted to the arms 32 through the loose or pin and slot connections 40-41 between the two sets of arms.

The paper feeding and pressure devices further comprise a pair of guiding members or fingers arranged at the front side of the platen and adjustable lengthwise thereof. Each finger, designated as a whole by the numeral 42, is preferably made of a single piece of sheet metal and comprises an upright portion 43 and an integral horizontally disposed portion 44 at right-angles thereto. The finger portion 43 extends crosswise of the printing line and is provided at its upper end with a pressure roll 45 which bears rotatably on a headed screw pivot 46 that is carried by the finger portion 43. The upper end of the portion 43 is curled at 43^a (Fig. 1) to provide a support for the shank of the screw pivot 46. The horizontal portion 44 is provided at its lower side in line with the finger portion 43 with a contact device 47 which is effective to operate certain line locking mechanism not comprised in our present invention but which is disclosed and claimed in the application of Arthur W. Smith, Sr. No. 515,890, filed Nov. 17, 1921. The horizontal portion 44 is also provided near its ends with pairs of clips or engaging devices 48 which are struck from the sheet metal of the part 44 itself and fit over a rectangular supporting bar 49. Said bar extends lengthwise of the platen at its front side and below the printing line, and the paper guiding devices or paper finger contrivances 42 are slidably mounted on said bar. The front face of the bar is preferably grooved or undercut to provide a seat for an inset scale 50, and the edge 51 of the paper finger cooperates as a pointer with said scale to facilitate the lengthwise adjustment of the paper finger contrivances in respect to the platen. Near its ends the bar 49 is provided with rearwardly extending lugs 52 that are perforated to bear on extensions or pins 53 projecting outward from the forward ends of the bracket arms 23. These arms, it may be noted, are bendable so as to afford adjustment of the paper finger supporting bar 49 both in an up and down direction and also away from and back towards the front face of the platen. Said arms extend forward under the platen and are provided with side lugs 22^a to which are secured by headed screws 54 springs tongues 55 that bear at their free ends against the rear ends of the lugs 52, thus tending to turn the bar 49 on its pivots 53 and maintaining the pressure rolls 45 in spring pressed engagement with the platen for the paper thereon above the printing line.

Other of the paper guiding devices com-

prise a shield, apron or deflector in the form of a curved plate 56 of sheet metal which is arranged under the platen and is cut out or slotted at its rear and front edges to accommodate respectively the sections 15 of the main feed roller and the sections 30 of the secondary feed rollers, leaving projecting portions or lips 57 and 58 between the roller sections. Near its ends the deflector or guide plate 56 is provided with clip devices 59 and 60. These pairs of fingers are secured at their forward ends to the bottom of the deflector plate by rivets 61, and their rear end portions are free and adapted to be pressed apart to accommodate or seat pins 62 on which the deflector plate is pivotally supported. The lower finger 60 of each pair is depressed to provide a seat for the pin 62 and the construction is such that when the platen is removed the deflector plate may be readily detached by pulling it forward and upward, causing the clip members or fingers 59, 60 to yield or spread to release the pins 62. On the other hand, the deflector plate may be readily replaced, the ends of the fingers 59 and 60 being so shaped that when they are pushed against the pins they will spread or separate so as to reengage with the pins. Said pins 62 are supported on and project laterally from ears 63 which are bent upward from angular plates 64 fixed to the back bar 3 of the carriage by the screws 26, the plates 64 resting on the brackets 22-25.

The guiding devices further include a paper table preferably formed of two plates or table parts 65 and 66 which are hinged together so that they are capable of relative movement. The plate 65 is inclined upward and rearward behind the platen so as to form a bight therewith to receive the paper when it is inserted. The lower end of the plate 65 is formed with long and short fingers numbered respectively 67 and 68, which fingers are so disposed along the lower edge of the table or plate 65 that they co-operate with the feed roll sections 15 and the rear projecting lips 57 of the deflector 56 to provide a comparatively uninterrupted surface over which the paper may be introduced. Thus the fingers 68 terminate just above the tops of the feed roller sections 15 while the longer fingers 67 project downward between the feed roller sections and close to the rear edge portions of the projections or lips so that no opening is afforded through which the edge of the paper might accidentally slip down or be introduced to cause trouble. The plate or table portion 65 is fixed to the carriage of the machine by screws 69 which are threaded into depressed portions 25^a of the bar portions or bracket arms 25. These depressed portions 25^a accommodate corresponding de-

pressions or countersinks 65^a in the surface of the plate 65, enabling the heads of the screw, 69 to be countersunk below the surface of the plate 65, so that there may be no obstruction or projection to interfere with the smoothness of introduction of paper over this surface. At its ends the plate 65 is provided with upwardly extending arms 70 between which the plate is bent or inclined rearward, providing a lip 71. The arms 70 are riveted or otherwise secured to the rear of the plate 65 and are made of stock sufficiently thick to enable it to be perforated or bored out to provide bearing openings for a pivot rod 72, which extends lengthwise of the plate 65 slightly above the lip 71. The pivot rod 72 is fixed to the plate or upper table portion 66 which is provided near its ends with eye-members 73 fitting over the rod 72, said rod being fixed thereto by cross pins 74. Thus the pivot rod 72 and the plate 66 are secured rigidly together and the construction is such that the plate or table portions 66 may be swung forward on its bearings in the arms 70 so as to afford access to various stop devices or other parts, not shown, which are arranged behind and below the table part 66. This part, as will be seen from Fig. 1, is angular in cross section and its upper surface is normally substantially horizontal while its forward inclined portion is in line with the lower plate 65, which wholly supports the part 66. The lower edge of the plate 66 is curved rearward to provide a lip 75 in correspondence with the lip 71, these two lips co-operating with the rod 72 to give a finished appearance to the two-part paper table. The upper end portions of the arms 70 act as stops to limit backward rotation of the plate 66, and assist to maintain it in normal position illustrated in Fig. 1.

The main and secondary feed rollers and the paper deflector or apron, together with the paper finger contrivances, are simultaneously releasable or movable out of operative engagement with the platen by hand operated releasing devices. Said releasing devices comprise the rock shaft 33 to which are secured a set of releasing fingers 76 provided with hub portions 77 that fit over the shaft 33 and are secured thereto by cross pins 78. From the hubs 77 project integral arms 79 which terminate in lateral extensions or fingers 80 which overlie and are adapted to contactively engage with pins 81 fixed to and projecting laterally from the neighboring arms 18, said contactive engagement taking place when the shaft 33 is rocked. To rock or operate the shaft 33 it is associated with devices comprising a crank arm 82 which is arranged outside the left-hand carriage plate 4, said crank arm being provided with a hub 83 which fits over and is pinned to a stub shaft 84. This shaft 84, as will be understood from Fig. 3, is arranged in line with the rock shaft 33, the stub shaft 84 bearing in a perforation in the left-hand plate 4, and the inner end of said stub shaft terminating close to the left-hand end of the shaft 33. The end of the crank arm 82 is pivotally connected at 85 with a lever or toggle member 86 which extends upward behind the left-hand axle 9 and curves forward normally over the top of said axle, as clearly shown in Fig. 2, said lever member 86 terminating in a laterally bent finger portion or release key 87. The lower end of the lever member 86 below its pivotal connection 85 is pivotally connected at 88 with a link or toggle member 89 which is pivoted at 90 to the outer face of the bar or plate 4. The pivot 90 is a flanged eccentric device which is rotatably adjustable on a headed clamping screw 90^a which passes through the eccentric 90 and is threaded into the end bar 4.

As appears from Fig. 3, the abutting ends of the shaft 33 and the stub shaft 84 are housed or covered by an elongated hub 91 from which at its left-hand end projects a forwardly extending crank arm 92 terminating in an upstanding nose or contact 93. The hub 91 is fixed to the shaft 33 by a cross pin 94, the construction being such that the crank arm 92 and the shaft 33 are rigid with each other while the outer or left-hand end portion of the hub 91 provides a socket which fits over the inner end of the stub shaft 84. Welded to or otherwise secured to the inner end portion of the stub shaft between the plate 4 and the crank arm 92 is a crank arm 95 which is parallel with and contiguous to the crank arm 92. The two crank arms are connected by a pin and hole connection, a lateral pin 96 extending rightward from the free end of the crank arm 95 and fitting in a hole in the crank arm 92. The construction is such that rocking motion received by the stub shaft 84 from the key 87 is transmitted to the rock shaft 33 through the two connected crank arms 95 and 92, the two shafts 84 and 33 operating in effect as a single shaft. It may be noted here that the purpose of the two-shaft construction is to permit the detachment and removal of the shaft 33 and associate parts without disturbing or affecting the shaft 33 and the connections associated with it outside the end plate 4, said connections comprising the members 86 and 89. It will be understood that all that is necessary to disconnect the two shafts is to drive out the pin 94 and then slip the hub 91 rightward along the shaft 33 until said hub disengages from the stub shaft 84. The nose 93 in which the crank arm 92 terminates underlies an arm 97 rigid with and projecting rearward from the paper finger bar 49 near the left end of the latter. The parts 92, 97 provide an opera-

- tive connection between the rock shaft 33 and the bar 49 and paper finger contrivances 42. The normal relationship of the members 89 and 86 is illustrated in Fig. 2, which shows 5 the toggle broken as it appears when the feed rollers and the paper fingers are operative. In order to release the paper feed devices the finger piece 87 is pushed backward with the result that the crank arm 82 is 10 turned rearward and the shafts 84 and 33 rocked rearward. This has the effect of depressing the extensions 80, causing them to act against the pins 81 to swing down the arms 18 against the pressure of springs 15 29 and carry the main feed roller sections 15 away from the platen, or from the Fig. 1 to the Fig. 4 position. The downward swing of the arms 18 operates through the pin and slot connections 40, 41 to overcome 20 the springs 38 and swing the arms 32 downward, thus releasing the secondary feed rollers 30, as shown in said Fig. 4; and at the same time the deflector 56 drops down around its pivots 62 away from the platen. 25 The rocking of the shafts 84 and 33 as described also acts to swing upward the crank arm 92, causing the nose 93 to press against the under side of the arm or crank 97, turning the bar 49 on its pivots 53 and swinging 30 the paper fingers 42 forward to released position, as shown in Fig. 4. The paper feeding devices will be held in inoperative or released position as shown, due to the straightening out and consequent locking of 35 the toggle parts 89, 86. In order to restore the parts to operative engagement with the platen the release key 87 is pulled forward, breaking the toggle and allowing the restoring springs to become effective on their associate parts to return them against the 40 platen.
- Our present invention provides paper feeding and controlling mechanism, the elements whereof may to a great extent be 45 readily removed one at a time without the aid of tools. Said mechanism as a whole may also be readily detached, as it is for the most part mounted on a pair of detachable brackets; and as a preliminary to detaching the brackets and removing the 50 mechanism as a whole it is merely necessary to take out the rod 21. For example, the platen may be removed when the pins or plungers 13 are somewhat retracted, thus 55 leaving the deflector 56 exposed so that it may be detached by pulling it out, the spring fingers 59 and 60 readily releasing the pivot pins 62. Thereupon the main or secondary feed rollers may be lifted out of 60 place, the different springs may be removed, the paper finger bar and paper fingers may be detached by forcing out the pivot pins 52, and so forth. Another useful feature of the invention is that the main part 33 of 65 the release shaft may be removed with
- other parts of the mechanism that are arranged between the two end bars of the carriage, without disturbing either the short part 84 of the release shaft or the key connections to said shaft that are mounted on 70 the outer face of the left-hand end bar 4, these connections comprising the arm 86, crank arm 82 and the toggle arm 89. Thus there are avoided most of the disconnections, 75 reconnections and readjustments which have heretofore been necessary when some of the parts are mounted inside the carriage frame and some outside with connections extending through the frame.
- Various changes may be made without 80 departing from our invention.
- What we claim as new and desire to secure by Letters Patent, is:—
1. In a typewriting machine, the combination of a carriage, a platen, a feed roller device comprising a rod or shaft and roller sections mounted thereon, pivoted slotted arms supporting said rod, and spring means for independently pressing said arms towards the platen, said rod being of small 90 diameter to fit freely in the slots in said arms and also in order to yield readily to assist in compensating for inequalities during feeding operations.
  2. In a typewriting machine, the combination of a carriage, a platen, a feed roller device comprising a rod and a plurality of roller sections mounted thereon, a plurality of pivoted arms supporting said rod, and detachably mounted bow springs, one for 100 each supporting arm, said springs constantly pressing said arms towards the platen independently of each other, said springs holding themselves in place by friction.
  3. In a typewriting machine, the combination of a carriage, a platen, a feed roller device comprising a rod and a plurality of roller sections mounted thereon, a plurality of pivoted arms supporting said rod, a shaft carried by the carriage and on which said arms are pivoted, and springs, one for each arm, said springs loosely embracing said shaft and each having a branch which engages near its free end with the projection on the associate arm, the opposite branches 115 of said springs resting on an abutment on the carriage, said springs holding themselves in place by friction.
  4. In a typewriting machine, the combination of a carriage, a platen, a shaft carried by the carriage, slotted arms provided with laterally extending hubs rotatably supported on said shaft, a feed roller provided with an axle, said axle bearing in the slots in said arms, bow springs loosely embracing said hubs and engaging lateral pins on said arms, and an abutment on the carriage with which all of said springs frictionally engage.
  5. In a typewriting machine, the combi- 130

- nation of a carriage, a platen, a shaft carried by the carriage, slotted arms provided with laterally extending hubs rotatably supported on said shaft, a feed roller provided with an axle, said axle bearing in the slots in said arms, bow springs loosely embracing said hubs and engaging lateral pins on said arms, an abutment on the carriage with which all of said springs frictionally engage, a bar rotatably supported on the carriage, a paper finger adjustable along said bar, and springs co-operating with said bar to maintain said paper finger in engagement with the platen.
- 15 6. In a typewriting machine, the combination with a carriage, a platen, brackets detachably supported on said carriage, a rod or shaft supported by said brackets, arms carried by said rod or shaft, a feed roller supported by said arms, a paper finger rod or bar rotatably supported by said brackets, and a paper finger adjustable on said rod or bar.
7. In a typewriting machine, the combination with a carriage, a platen, brackets detachably supported on said carriage, a rod or shaft supported by said brackets, arms carried by said rod or shaft, a feed roller supported by said arms, a paper finger bar provided with lugs, pivot pins connecting said lugs with said brackets, and a paper finger adjustable along said bar.
8. In a typewriting machine, the combination with a carriage, a platen, brackets detachably supported on said carriage, a rod or shaft supported by said brackets, arms carried by said rod or shaft, a feed roller supported by said arms, a paper finger adjustable on said rod or bar, and a paper table supported on said brackets.
9. In a typewriting machine, the combination with a carriage, a platen, brackets detachably supported on said carriage, a rod supported by said brackets, arms carried by said rod, a feed roller supported by said arms, a paper finger bar rotatably supported by said brackets, a paper finger on said bar, and a two-part paper table, the two parts being hinged together and one part being rigidly secured to said brackets.
10. In a typewriting machine, the combination with a carriage, a platen, brackets detachably supported on said carriage, a rod or shaft supported by said brackets, arms carried by said rod or shaft, a feed roller supported by said arms, a paper finger rod or bar rotatably supported by said brackets, a paper finger adjustable on said rod or bar, and a paper deflector pivotally supported from said brackets and provided with openings to accommodate the sections of said feed roller.
11. In a typewriting machine, the combination with a carriage, a platen, brackets detachably supported on said carriage, a feed roller supported by said brackets, a paper finger bar rotatably supported by said brackets, a paper finger on said bar, a paper deflector pivotally supported from said brackets, and a paper table also supported on said brackets.
12. In a typewriting machine, the combination of a carriage, a platen, bracket arms detachably secured at the rear of the carriage and projecting forward under the platen, a feed roller supported from said bracket arms, a bar arranged at the front of the platen and provided with rearwardly extending lugs, pivot pins connecting said lugs with the forward end portions of said bracket arms, and a paper finger on said bar.
13. In a typewriting machine, the combination of a carriage, a platen, brackets on the carriage, a feed roller supported from said brackets, a bar arranged at the front of the platen and provided with rearwardly extending lugs, pivot pins connecting said lugs with the forward end portions of said brackets, a paper finger on said bar, said paper finger having an edge which serves as a pointer in co-operation with said scale plate.
14. In a typewriting machine, the combination of a carriage, a platen, brackets detachably secured at the rear of the carriage and projecting forward under the platen, a feed roller supported from said brackets, a bar arranged at the front of the platen and provided with rearwardly extending lugs pivotally connected with said brackets, a paper finger on said bar, an arm extending rearward from said bar near one end, and key operated releasing devices co-active with said arm to turn said bar on its pivots and release said paper finger.
15. In a typewriting machine, the combination of a platen, a carriage, a bar supported thereon, and a paper finger provided with clips whereby said finger is slidably supported on said bar, said finger also being provided with a line-lock-operating projection.
16. In a typewriting machine, the combination of a platen, a carriage, a rectangular bar supported from said carriage, a one-piece sheet metal paper finger provided with clips slidably engaging said bar, the upper end of said paper finger being curled, a pivot supported by the curled portion of said paper finger, and a pressure roller on said pivot.
17. In a typewriting machine, the combination of a carriage, a platen, sectional feed rollers, a paper table at the rear of the platen and a paper deflector underlying the platen, said table and said deflector being provided with oppositely extending projec-

- tions which extend between the sections of said feed roller and co-operate to close the gaps between said sections.
18. In a typewriting machine, the combination of a platen, a carriage, and a two-part paper table in rear of the platen, the two parts of the paper table being hinged together and one part having its main portion normally horizontally disposed, the other paper table part being inclined and providing the sole support for the horizontally disposed part.
19. In a typewriting machine, the combination of a platen, a carriage, and a two-part paper table in rear of the platen, the two parts of the paper table being hinged together, one part carrying a cross rod fixed to it and the other part being provided with eyes fitting over said rod.
20. In a typewriting machine, the combination of a platen, a carriage comprising an inclined rear bar, a pair of brackets detachably secured to said bar, each bracket comprising a forwardly extending arm, a rearwardly extending inclined arm, and a portion connecting said two arms, feed roller devices supported on the forwardly extending arms of said brackets, and a paper table secured to the rearwardly inclined arms of said brackets.
21. In a typewriting machine, the combination of a platen, a carriage, paper feeding mechanism and releasing devices for said mechanism, said releasing devices comprising a two-part shaft, and disconnectible connections between the two shaft parts.
22. In a typewriting machine, the combination of a platen, a carriage, paper feeding mechanism, a two-part shaft, detachable connections between the two parts of said shaft, releasing devices mounted on one of the shaft parts for co-operation with the paper feeding mechanism, and a release key connected with the other shaft part.
23. In a typewriting machine, the combination of a platen, a carriage, paper feeding mechanism, a two-part shaft, a crank arm having a hub secured to one of the shaft parts, the other shaft part seating in said hub and being provided with a crank arm connected to the first recited crank arm by a pin and hole connection, releasing devices for the paper feeding mechanism mounted on said two-part shaft, and a release key for actuating said two-part shaft.
24. In a typewriting machine, the combination of a platen, a carriage comprising end bars, paper feeding mechanism, and key operated releasing mechanism comprising a two-part shaft, one shaft part being mounted on an end bar of the carriage and the other shaft part being detachable independently of the first recited part.
25. In a typewriting machine, the combination of a platen, a carriage comprising an end bar, paper feeding mechanism, and means for releasing said feeding mechanism, said means comprising a release key and a release shaft, said shaft comprising a long part and a short part detachably connected, the short part being mounted on said end bar and having a toggle connection with said release key, said release key and said toggle being supported on and outside of said end bar.
26. In a typewriting machine, the combination of a platen, a carriage comprising an end bar, paper feeding mechanism, and means for releasing said feeding mechanism, said means comprising a two-part shaft, a crank arm fixed to one shaft part, a toggle arm, and a release key having pivotal connections both with said toggle arm and with said crank arm.
27. In a typewriting machine, the combination of a platen, a carriage provided with end bars, paper feeding mechanism, and releasing means therefor, said means comprising a rock shaft, a release key, and connections for rendering said key effective on said shaft, said connections comprising a toggle arm and an eccentric on which said toggle arm bears, said eccentric being clamped adjustably to one of said end bars.
28. In a typewriting machine, the combination of a platen provided with an axle; a carriage comprising an end bar; paper feeding mechanism; and means for releasing said feeding mechanism, said means comprising a release shaft, devices thereon engageable with said paper feeding mechanism, and a vertically disposed arm connected to said shaft and terminating at its upper end in a finger piece or key, said arm normally curving forward over the axle of the platen outside the carriage end bar.
29. In a typewriting machine, the combination of a carriage, a platen, two sets of pivoted arms, feed rollers mounted on said sets of arms, the two sets of arms being connected by pin and slot connections between their several arms, spring means for normally maintaining said feed rollers in effective position, a key actuated rock shaft, and releasing connections between said rock shaft and the arms of one of said sets.
30. In a typewriting machine, the combination of a carriage, a platen, two sets of oppositely extending pivoted arms, feed roller devices one mounted on each set of arms, each arm of each set having a pin and slot connection with one of the arms of the other set, spring means for normally maintaining said feed roller devices in engagement with the platen, a key controlled rock shaft, projections on said rock shaft, and pins one projecting laterally from each of the arms of one of said sets, said projections co-operating with said pins.
31. In a typewriting machine, the combination of a platen, a carriage comprising

- bination of a platen, a carriage comprising end bars between which the platen is supported, paper feeding mechanism co-operative with said platen between said end bars,
- 5 releasing means comprising parts arranged between said end bars and co-operative with said paper feeding mechanism, other parts of said releasing means being arranged outside of the carriage frame and supported
- 10 on one of the end bars, and connections between the parts of the paper releasing means inside the carriage frame and the parts out-

side of said carriage frame which connections afford removal of the parts of one group without disturbing the other parts. 15

Signed at the borough of Manhattan, city of New York, in the county of New York and State of New York, this 15th day of August, A. D. 1922.
